UNITED STATES PATENT OFFICE.

JOHN M. FEEDERS, OF BUFFALO, NEW YORK, ASSIGNOR TO FEEDERS MANUFACTURING COMPANY, INC., OF BUFFALO, NEW YORK, A CORPORATION OF NEW YORK.

RADIATOR.

1,274,402.

Specification of Letters Patent.

Patented Aug. 6, 1918.

Application filed October 15, 1917. Serial No. 196,809.

To all whom it may concern:

Be it known that I, JOHN M. FEEDERS, a citizen of the United States, residing at Buffalo, in the county of Erie and State of New York, have invented new and useful Improvements in Radiators, of which the following is a specification.

This invention relates to that class of radiators which are more particularly designed for cooling the water of gas engines and has for its object the provision of means whereby this can be accomplished economically and efficiently and in a manner which will increase the strength of the radiator and also permit the same to be manufactured expeditiously by the employment of comparatively unskilled help.

In the accompanying drawings: Figure 1 is a fragmentary front view, partly in section of a radiator core constructed in accordance with my invention. Fig. 2 is a horizontal section taken on line 2—2 Fig. 1. Fig. 3 is a perspective view of one of the radiating members or sections interposed between adjacent water tubes of the radiator.

Similar characters of reference refer to like parts throughout the several views.

1 represents a plurality of water tubes or passages which are arranged side by side and which are adapted to be connected at their opposite ends with the water circulating system of the gas engine for the purpose of reducing the temperature of the water and cooling the engine accordingly. Each of these water tubes is constructed of two strips 2, 2 of sheet metal which are bent into corrugated form which strips are so assembled that they form opposite walls of a tube and are provided at their corresponding longitudinal edges with off-sets 3 which are connected with each other by solder or other suitable means. A plurality of such tubes are arranged side by side so that adjacent water tubes are spaced apart and the valleys or bottoms of the corrugations on the exterior of one tube wall are arranged transversely in line or opposite to the external valleys or bottoms of the opposing wall of an adjacent tube.

Between every two adjacent water tubes is arranged a plurality of radiating members or sections which operate to dissipate the heat of the tube walls to the atmosphere. 55 Each of these radiating members comprises

a longitudinal web 4 and two transverse flanges 5, 5 arranged at opposite side edges of the web, one of these flanges being arranged at right angles to this web and projecting laterally therefrom in one direction while the other flange is also arranged at right angles to the web and projects laterally therefrom in the opposite direction so that this web and these two flanges together are of substantially Z-shaped form in cross section. At suitable intervals the web of each of these radiating members is provided with retaining lips 6 which are struck out of the stock of this web, some of these lips being bent and formed so that they project from one side of this web opposite to one of the flanges and are arranged in line therewith while others of these lips project from the other side of this web and in an opposite direction from the other flange, but in line with the latter. The web, flanges and lips of each radiating member are preferably constructed integrally from a single sheet of metal by means of suitable dies.

In assembling the radiating members, a plurality of the same are arranged in a longitudinal row between two opposing walls of a pair of adjacent water tubes so that the flange and lips at one side edge of each web engage flatwise with the lips and flanges at one side edge of an adjacent radiating member, and the outer edges of these lips and flanges engage with the valleys or bottoms of corresponding corrugations of a pair of adjacent water tube walls. When thus assembled the several webs of a set or group of radiating members between two water tubes are arranged lengthwise in line and these radiating members together with these tube walls form two longitudinal rows of air passages 7 through which the air passes from one side of radiator to the other for the purpose of carrying away the heat from the tube walls and the radiating members. These radiating members are retained in place between the tube walls preferably by soldering opposite ends thereof to the walls.

By thus constructing each radiating member, the same forms an efficient means for aiding in cooling the water and it also effectively braces the water tubes relatively to each other so that the radiator as a whole is very strong.

Owing to the simplicity of this construction the several parts can be readily assem-

bled by persons having little skill without liability of misplacing the parts or impairing the efficiency or strength of the radiator.

By this formation of the retaining lips on each radiating section the same when placed between two water tube walls is not liable to tip or tilt out of place, but is retained in its properly aligned position relatively to adjacent radiating members and as these lips are struck out of the webs no waste of material nor added cost is incurred.

Furthermore, the openings 8 which are formed in the web by striking out the retaining lips therefrom provide means for permitting a cross circulation of the air in the radiating core and thereby equalizing the radiating efficiency of the same.

I claim as my invention:

1. A radiator comprising a plurality of water tubes one wall of each tube being arranged opposite and spaced apart from a wall of an adjacent tube, and a radiating member arranged between adjacent tubes and having a longitudinal web, a flange arranged at one side edge of the web and projecting laterally therefrom in one direction into engagement with one wall of one of said tubes, another flange arranged on the other side edge of said web and projecting laterally therefrom in the opposite direction into engagement with one wall of another tube, and retaining lips projecting in opposite directions from said web into engagement with the opposing walls of two adjacent water tubes.

2. A radiator comprising a plurality of water tubes, one wall of each tube being arranged opposite and spaced apart from a wall of an adjacent tube, and a radiating member arranged between adjacent tubes and having a longitudinal web, a flange arranged at one side edge of the web and projecting laterally therefrom in one direction in engagement with one wall of one of said tubes, another flange arranged at the other side edge of said web and projecting laterally therefrom in the opposite direction into engagement with one wall of another tube, and retaining lips struck out of said web and projecting in opposite directions therefrom into engagement with the opposing walls of two adjacent water tubes.

3. A radiator comprising a plurality of water tubes, one wall of each tube being arranged opposite and spaced apart from a wall of an adjacent tube, and a radiating member arranged between adjacent tubes and having a longitudinal web, a flange arranged at one side edge of the web and projecting laterally therefrom in one direction in engagement with one wall of one of said tubes, another flange arranged at the other side edge of said web and projecting laterally therefrom in the opposite direction into engagement with one wall of another tube,

and retaining lips struck out of said web and arranged in line with said flanges, respectively, and projecting in opposite directions into engagement with the opposing walls of two adjacent water tubes.

70

4. A radiator comprising a plurality of water tubes, one wall of each tube being arranged opposite and spaced apart from the wall of an adjacent tube, and a radiating member arranged between adjacent tubes and having a longitudinal web, a flange arranged at one side edge of the web and projecting laterally therefrom in one direction into engagement with one wall of one of said tubes, another flange arranged at the other side edge of said web and projecting laterally therefrom in the opposite direction into engagement with one wall of another tube, and retaining lips projecting in opposite directions from said web into engagement with the opposing walls of two adjacent water tubes, said water tube walls being corrugated and the flanges of said radiating member engaging with the valleys of corresponding corrugations on the opposing walls of two adjacent water tubes.

85

5. A radiator comprising a plurality of water tubes, one wall of each tube being arranged opposite and spaced apart from a wall of an adjacent tube, and a radiating member arranged between adjacent tubes and having a longitudinal web, a flange arranged at one side edge of the web and projecting laterally therefrom in one direction in engagement with one wall of one of said tubes, another flange arranged at the other side edge of said web and projecting laterally therefrom in the opposite direction into engagement with one wall of another tube, and retaining lips struck out of said web and projecting in opposite directions therefrom into engagement with the opposing walls of two adjacent water tubes, said water tube walls being corrugated and the flanges of said radiating member engaging with the valleys of corresponding corrugations on the opposing walls of two adjacent water tubes.

95

6. A radiator comprising a plurality of water tubes, one wall of each tube being arranged opposite and spaced apart from a wall of an adjacent tube, and a radiating member arranged between adjacent tubes and having a longitudinal web, a flange arranged at one side edge of the web and projecting laterally therefrom in one direction in engagement with one wall of one of said tubes, another flange arranged at the other side edge of said web and projecting laterally therefrom in the opposite direction into engagement with one wall of another tube, and retaining lips struck out of said web and arranged in line with said flanges, respectively, and projecting in opposite directions into engagement with the opposing walls of two adjacent water tubes, said water tube

- walls being corrugated and the flanges of said radiating member engaging with the valleys of corresponding corrugations on the opposing walls of two adjacent water tubes.
- 5 7. A radiator comprising a plurality of water tubes having corrugated walls, the valleys of the corrugations of one wall of each tube being arranged opposite the valleys of the corrugations of one wall of an adjacent tube, and a plurality of radiating members arranged in a row and each com-
- prising a central longitudinal web, flanges projecting laterally in opposite directions from opposite edges of said web into engagement with corresponding valleys on the 15 outer side of two opposing walls, and retaining lips struck out of said web on opposite sides thereof and each arranged in line with one of said flanges and projecting in an opposite direction and engaging with the valley of a corrugation in an adjacent tube wall. 20
